UNITED STATES PATENT OFFICE.

SAMUEL MATHEWS, OF McCURTAIN, OKLAHOMA.

DEVICE FOR COOLING TWYER-IRONS.

1,365,333.

Specification of Letters Patent. Patented Jan. 11, 1921.

Application filed January 6, 1920. Serial No. 349,810.

To all whom it may concern:

Be it known that I, SAMUEL MATHEWS, a citizen of the United States of America, and resident of McCurtain, in the county of 5 Haskell and State of Oklahoma, have invented certain new and useful Improvements in Devices for Cooling Twyer-Irons, of which the following is a specification.

This invention relates to forges and particularly to means for preventing the burning of twyer irons, the said invention having for its object the provision of novel means for maintaining the temperature relatively low without affecting the fire, the 10 said device including novel means for creating a circulation of water in close proximity to the twyer iron without detrimentally affecting the entrance of air current from the blower.

20 A still further object of this invention is to provide a member having an annular channel with branches leading therefrom to permit the circulation of fluid which will tend to maintain the temperature practically uniform.

With the foregoing and other objects in view, the invention consists in the details of construction, and in the arrangement and combination of parts to be hereinafter more 30 fully set forth and claimed.

In describing the invention in detail, reference will be had to the accompanying drawings forming part of this specification wherein like characters denote corresponding parts in the several views, and in 35 which—

Figure 1 illustrates a sectional view of a twyer with the blower and device embodying the invention in operative relation 40 thereto;

Fig. 2 illustrates an enlarged detail view, partly in section showing a device embodying the invention; and

Fig. 3 illustrates a longitudinal sectional 45 view of the circulating pipe.

In these drawings 5 denotes a twyer iron which may be of any appropriate construction and I do not wish to be limited with respect to this element or the manner in 50 which it is formed, but I employ in connection with it an air pipe 6, the central portion of which has a passage for air, the said

pipe having a double wall forming an annular chamber 7 with closed ends through which water may circulate, and the said 55 pipe may be said to be jacketed, as shown in Fig. 3.

In order to install the invention in operative relation to the twyer, suitable brackets such as 8 may be employed for supporting 60 a receptacle or barrel 9, and the said receptacle has a faucet 10 in communication with it, so that fluid within the receptacle 9 may flow through the faucet. A nipple 11 connects the faucet with the annular chamber 65 of the pipe 6 and the pipe 12 connects the said annular chamber with the receptacle 9 so that fluid will pass from the receptacle into the annular chamber and after it is expanded by the heat of the fire on the twyer, 70 the said fluid will be forced through the pipe 12 to the tank or receptacle 9 and thus the water within the tank will continue to circulate being cooled while it is outside of 75 the annular chamber so that over-heating of the twyer will be prevented.

A drain nipple or cock 13 is tapped into the outer wall of the pipe so that the same may be drained to prevent freezing.

In installing the invention, I connect the 80 outer end of the pipe to a conduit or tube 14 leading from the blower 15 and I do not wish to be restricted with respect to this arrangement of parts as any convenient means may be provided for supplying air to the 85 pipe as is common in storage constructions, but it has been found in practice that the device is very effective in preventing formation of clinkers and in protecting the twyer iron whereas the expense of installation and 90 maintenance is comparatively small, in fact the expense of maintenance is *nil*.

I claim—

1. In a device for cooling twyer irons, an air pipe extending into the twyer iron, a 95 jacket surrounding the twyer iron and forming an annular chamber, means for supplying fluid to the said chamber, means for conducting fluid from the chamber and a receptacle from which the first mentioned 100 means conducts the fluid and to which the second mentioned means conducts the fluid.

2. In a device for protecting twyer irons, a pipe having a jacket embracing the same

and spaced therefrom to form an annular chamber with closed ends, a pipe threaded to the jacket and communicating with the annular chamber, a receptacle to which the 5 said pipe discharges, a faucet in communication with the receptacle for receiving fluid therefrom, means of communication

between the faucet and the said annular chamber through the jacket, a drain cock threaded in the said jacket, a blower, and 10 means of communication between the blower and the interior of the pipe.

SAMUEL MATHEWS.
